UNITED STATES PATENT OFFICE.

EDWARD B. IVES, OF WEST POINT, NEW YORK.

PHOTOGRAPHIC-PLATE HOLDER.

SPECIFICATION forming part of Letters Patent No. 246,140, dated August 23, 1881.

Application filed April 20, 1881. (No model.)

To all whom it may concern:

Be it known that I, EDWARD B. IVES, of West Point, in the county of Orange and State of New York, have invented a new and useful Improvement in Photographic-Plate Holders, of which the following is a specification.

My invention relates to a device for holding the sensitive plate for insertion in and removal from the camera.

10 The invention consists, essentially, in a novel mode of constructing the holder by attaching together a number of layers of material in the manner hereinafter more particularly described.

In the accompanying drawings, Figure 1 is a front view of a device embodying my improvements with the plate in place. Fig. 2 is a longitudinal section taken in the line *x x* of Fig. 1. Fig. 3 is a transverse section taken in the line *y y* of Fig. 1.

20 Similar letters of reference indicate corresponding parts.

The material composing the holder may be metal, wood, paper, card-board, or any other suitable substance; but I prefer to use paper or card-board.

25 A represents a rectangular piece, which forms the back or bottom of the holder.

B is a piece of the same exterior dimensions, having a rectangular piece of the same size as 30 the plate to be carried cut from its center, leaving a border, *b*, around its four sides or edges.

C is a similar piece, but with a larger piece cut from it, and consequently having its border *c* narrower than the border *b*.

D is a similar piece, except that its border *d* extends only on three sides, leaving the upper edge open.

E is a piece similar to the piece C, having 40 its border *e* extending around its four sides.

G is a dark-shutter, adapted to slide in and out between the pieces C and E, with its edges engaging with and guided by the grooves formed by the inner and outer sides of the 45 borders *c* and *e* and the inner edges of the border *d*, when the five pieces are secured together to form the holder, which securing may be accomplished by gluing, riveting, or any other suitable means, according to the nature 50 of the material employed.

The plate *P* is placed in the opening formed in the piece B, with the back of the plate rest-

ing against the back or bottom A, in which position it is held by buttons *m*. It is held steadily in place and prevented from vibrating 55 by bending or curving the back or bottom A, or by interposing between the bottom and the plate a spring, or a piece of rubber, felt, or other suitable substance.

The top of the opening in which the shutter 60 G slides may be made impervious to light by means of a cut-off, *H*, of velvet or other suitable material. The lower corners of the shutter G are rounded, and its bottom edge between said corners is concave, so that when 65 the shutter is pushed into place the rounded corners first engage with the corners of the groove, and thus insure the proper engagement of the remainder of the lower edge by causing the concave edge to ride on the edge 70 of the groove in case of either part being warped or sprung.

In the ordinary holder the negative is inserted from the rear, with its face inward, and a hinged back is closed upon it. When this 75 back is not closed perfectly tight light is liable to be admitted to the plate.

By making my holder with its back perfectly tight, and inserting the plate from the front, with its back toward the closed back 80 or bottom of the holder, the accidental admission of light is rendered impossible.

Having thus fully described my invention, I claim as new and desire to secure by Letters Patent—

1. As an improved article of manufacture, a photographic-plate holder constructed of thin layers A B C D E of card-board, substantially in the manner and for the purpose herein described.

2. The sliding dark-shutter G, in combination with a holder constructed of layers of card-board, provided with a groove formed by the borders *c*, *d*, and *e*, substantially as and for the purpose herein described.

3. In a photographic-plate holder, the shutter G, having rounded lower corners, and between said corners a concave bottom edge, as and for the purpose specified.

EDWARD B. IVES.
